R. M. Morris
ATTORNEY

UNITED STATES PATENT OFFICE

NORMAN WALLACE, OF CUMBERLAND, MARYLAND, ASSIGNOR TO KELLY-SPRINGFIELD TIRE COMPANY, OF CUMBERLAND, MARYLAND, A CORPORATION OF NEW JERSEY

SHOE SOLE

Application filed December 24, 1930. Serial No. 504,463.

This invention pertains to improvements in the so-called "composite" type of sole as applied to boots and shoes, and while the preferred illustration discloses a partial or 5 "half sole" attached as a facing on the conventional sole, it will be understood that the term "sole" is intended to embrace the accepted interpretation of such term in the art, except as to specific limitations herein set 10 forth.

There are, basically, two types of composite soles—that which is either sewed or nailed as a principal means of security to the welt and/or to a sole intended to be supplemented, and that type which relies upon adhesion by cementing and/or vulcanizing to a sole which is to be supplemented. This invention pertains specifically to the adhesion type, with or without the additional security 15 of marginal attachment by sewing or nailing, and is peculiarly well adapted to serve as a supplemental facing on a new shoe sole or to serve as a repair facing for one partially worn.

25 An appraisal of the objects attained by this invention can only be had by consideration of the fundamental principles availed of in its execution, as briefly summarized.

It is well-known that rubber compositions 30 may be utilized for shoes soles, with or without various inclusions of foreign substances—chiefly fibrous substances, textile insertions, etc. It is recognized that rubber may be compounded to afford amazing resistance 35 to abrasion, for example the conventional tread stock on automobile tires is known to sustain quite expected mileages of upward of 20,000 miles; but it is likewise recognized that such tread stock possesses characteristics 40 of relative stiffness, tendency to heat, separate and to crack which would render it useless unless in the design of it associated elements of the casing due consideration be taken of the necessity for so relating the other component parts as to physical characteristics 45 and proportion that the performance of the whole may be coordinated to best advantage.

The analogy of the well-known structure 50 of the automobile tire as to its necessary characteristics in service and the shoe sole of this

invention is availed of in realizing the novelty of the means devised to attain the resulting efficiency.

The load on the human foot is transmitted through the extremely flexible and yielding 55 ball portion to the zone of the shoe sole, that must be designed to receive it in such manner that the concentrated stresses shall be absorbed, transmitted and dissipated into the structure to the best advantage.

In short, it has become the chief object of this invention to produce a composite sole composed of laminated plies of unified material having different and modifying characteristics to most effectively meet the conditions of service; and specifically to provide an article that will be durable, flexible, thin and of light weight, cool wearing, comfortable to the wearer, waterproof, inexpensive, slightly and readily and efficiently applied by the unskilled.

These and other objects, and specific structural features, will be more fully developed throughout the following discussion, and the appended drawings illustrate a preferred 75 form and embodiment of the invention.

Figure 1 is a top plan view of an untrimmed sole in process of being fitted to a shoe.

Figure 2 is a top plan view, enlarged, of 80 the sole, trimmed, and with portions of the component layers broken away to illustrate structural features.

Figure 3 is a sectional view on the line 3—3 of Figure 2, showing the relationship 85 of the sole with the shoe structure, as applied and trimmed.

The illustrated embodiment comprises a thin and tough wear resisting rubber compound 17 in which is intimately embedded 90 a sheet 16 of relatively high twist, close-mesh square woven cotton fabric of a preferred construction of about seventeen squares per inch. This sole fabric 16 may be advantageously rubber coated, or frictioned and coated 95 in the well-known manner. The compound used on 16 is such that the maximum adhesion is induced with the relatively stiff tread stock 17, whereby the two supplement each other and work as a unit with fabric 100

16 transmitting stresses to underlying laminations and serving as an efficient unifying means thereto.

The layer 15 of cushion rubber, of appropriate thickness, is applied on rubberized fabric 16 and serves not only as an efficient cushion member to transmit and distribute stresses from the tread, but unifies these layers with the superposed open mesh cushion breaker 14. The cushion breaker 14, as also the top breaker 13, are preferably of open-mesh square woven cotton fabric of a preferred construction of about twelve squares per inch. These breakers further cushion, dissipate and transmit stresses from adjacent plies. They are heavily rubber coated in the usual manner with appropriate compounds which penetrate the interstices to form flexible rivets when the whole is finally vulcanized.

The breaker 15 is marginally stepped back from the trim line of the sole, and the breaker 14 is likewise marginally stepped back in relation to 15, for the purpose presently explained.

The top gum ply 12 overlays breaker 13 and is coextensive with the marginal dimension of the sole in order that a full attaching surface may be presented to the portion of the shoe with which it is to become associated. It is preferred that the well-known cold cementing process be followed in attaching the sole to the shoe portion, but due to the embedded thread fabric 16 in the tread 35 ply it is quite feasible to sew or nail the sole to the shoe with or without supplemental cementing.

This top gum 12 is so compounded as to form an intimate union with the portions of 40 all of the underlying plies with which it contacts.

An efficient manufacturing process consists in; mechanically coating a web of fabric 16 with soft rubber on both sides and then applying additional coats of the tough tread stock 17 to the desired thickness, and thereafter die cutting the so-prepared layer to a molded line 18 (see Figure 1); the soft unvulcanized cushion gum 15 of desired thickness 50 and of the same marginal dimension as 16—17 is then applied; thereafter the heavily coated breakers 14 and 13, die cut to diminished marginal sizes, are successively applied in the order named upon the surface of 15. At this stage the so-assembled units may be given a suitable vulcanizing treatment in a platen press, and thereafter the appropriately compounded unvulcanized top gum 12 is applied and firmly rolled into contact by the process 60 well known in the art. The migration of the vulcanizing elements of the underlying plies may be utilized as a further means for uniting the contacting surface of 12 thereto by subjecting the completely assembled sole to 65 a primary or secondary mild vulcanization

with the exposed top surface of raw gum 12 protected by a backing of glazed muslin or "Holland" (see Moony 1,068,691 of July 29, 1913); the resulting completed sole then consisting of a vulcanized tread and backing plies with the top shoe-attaching surface in a tacky, unvulcanized condition adapted to be united to a foreign surface under the usual cold cementing treatment.

The factory-made sole is preferably oversized to a molded line 18 in order that a marginal excess will afford ample trim-off to a line 19 when templated to the particular shoe sole to which it will be applied. It is preferable that the trim line 19 be slightly set back as at "A" from the margin of the shoe sole and that in the cutting operation a receding bevel "B" be worked (see Figure 3). This treatment has been found desirable to insure a snug fit and close adhesion of the sole 11 to the shoe bottom 10, without exposed edges to induce scuffing and marginal separation.

The progressive stepping back of breakers 13 and 14 with respect to the margin 19 and to each other serves the purposes of building up cushion depth and adhesive stress dissipating characteristics at the point of maximum effort under the ball of the foot, and especially provides for a marginally directed taper of the sole, as shown at Figure 3. This marginal taper beyond the breakers results in edges substantially thinner than the central portion, whereby the hazard of scuffing up the critical marginal attachment is reduced, and the thin edges greatly enhance the appearance of the assembled structure.

In Figure 3 the taper is exaggerated for illustrative purposes. In the preferred form it is found by actual measurement that the thickness of the margin, comprising plies 17, 16, 15 and 12 constitutes only approximately one-half of the central thickness, including the breakers 13 and 14. A preferred form of this sole discloses approximate thicknesses of one-eighth of an inch ($\frac{1}{8}$ ") and one-sixteenth of an inch ($\frac{1}{16}$ ") at the center and edges, respectively.

The inclusion of these breakers, either as a single ply or multiply plies as preferred, affords the essential depth of cushion; flexible unification between tread and attaching ply to dissipate and transmit stresses, and provides for absorption and dissipation of heat as an effective characteristic to add to the comfort of the wearer and contribute to the durability of the sole.

The marginal set back of the breaker element is such, in the different manufactured stock sizes of this article as to preserve the marginal taper when the final trim is made to accommodate the shoe structure with which it is intended to become associated; it being understood that these soles are regularly supplied to the trade in various stock sizes,

each of which has marginal excesses adapted to accommodate trimming to several sizes and widths of standard shoe lasts.

Extensive tests of these thin and ultra flexible soles have demonstrated wearing qualities equal to the performance of leather soles which they have substituted, without separation, and affording full comfort to the wearer.

It is apparent that various structural modifications and different and well-known manufacturing procedures may be resorted to as alternatives of the preferred description herein given without departing from the spirit of my invention as defined in the appended claims.

What I claim is:—

1. A relatively thin and flexible composite sole, comprising a ply of tough tread stock unified with a rubberized fabric backing; a cushion rubber ply thereon; a rubberized breaker on said cushion marginally short of the edges of said sole; and a cover ply of rubber on said breaker and coextensive with the margin of said sole, said cover having an unvulcanized exposed surface.

2. A relatively thin and flexible composite sole, comprising a ply of tough tread stock unified with a rubberized fabric backing; a cushion rubber ply thereon and substantially co-extensive therewith; a rubberized breaker on said cushion marginally short of the edges of said sole; and a cover ply of rubber on said breaker and coextensive with the margin of said sole, said cover having an unvulcanized exposed surface, said cover being intimately united with the portion of said cushion ply which extends marginally beyond said breaker whereby the assembled sole presents thin-edged tapering margins and a relatively thick central area.

3. A relatively thin and flexible composite sole, comprising plied tread, tread fabric and cushion rubber marginally coextensive; a plurality of breaker plies superposed on said cushion and progressively stepped back marginally from the edges of the tread; and a cover ply of rubber on said breaker plies having an unvulcanized exposed surface, said cover ply intimately united with the portion of said cushion which extends marginally beyond the breaker plies whereby the assembled sole presents thin-edged tapering margins and a relatively thick and more resilient central area.

4. A composite sole, comprising a relatively thin and tough tread ply; a relatively thick central area comprising rubberized resilient breaker elements; marginal areas relatively thin by omission of said breakers; and a cover ply of rubber having an unvulcanized exposed surface.

5. A composite sole, comprising a thin, tough, fabric-backed tread ply; a relatively thick central area comprising resilient cush-

ion and breaker elements; marginal areas relatively thin by omission of said breaker; and a cover ply of rubber substantially coextensive with the marginal dimension of said tread ply.

6. A composite sole, comprising a thin, tough, fabric-backed tread ply; a relatively thick central area comprising rubberized resilient breaker elements; marginal areas relatively thin by omission of said breaker, said areas tapering in depth from the thin to the thicker area; and a cover ply of rubber having an exposed surface adapted to be attached by cementing to a shoe bottom.

7. A composite sole, comprising a thin, tough, tread ply; a top ply of rubber having an unvulcanized exposed surface; resilient cushion and breaker inserts between the tread and top ply, said inserts tapering from a greater depth at the central area to a diminishing depth marginally.

8. A composite sole, comprising a thin, tough fabric-backed tread ply; a top ply of rubber having an unvulcanized exposed surface; substantially thick cushion and breaker inserts between the tread and top ply, said inserts forming a relatively thick pad over a substantial central area of said sole and marginally diminished in thickness whereby a sole with thin edges and relatively thicker center is formed.

9. A composite sole in blank adapted to be trimmed to a template, comprising a thin, tough, fabric-bound tread ply; a top ply of rubber having an unvulcanized exposed surface; textile rubberized breaker elements completely enveloped between said tread and top ply, said breaker elements forming a pad over a substantial central area of said sole; relatively thin marginal areas formed by contact of said tread and top ply whereby a trimming margin is provided without exposing the margins of said breaker elements.

10. A composite sole in blank adapted to be trimmed to a template, comprising a tread ply; a top cover ply of rubber having an exposed surface adapted to be attached to a shoe bottom by cement; said tread and top cover marginally unified to constitute a trimming excess; an enveloped central pad relatively thicker than the said margin, comprising a rubberized textile breaker insert having greater central than marginal depth.

11. A composite sole in blank, comprising a tough, thin, fabric-backed tread ply; a top cover ply of rubber having an exposed surface adapted to be attached to a shoe bottom by cement; an enveloped central pad of cushion gum and textile rubberized breaker fabric marginally stepped back from the edge of said tread ply and tapering centrally in thickness therefrom.

12. A composite sole in blank of vulcanizable elements, comprising a thin tread ply; a top cover ply having an unvulcanized exposed

surface; a cushion and rubberized breaker fabric constituting a cushion marginally tapered in thickness and completely enveloped by said tread and top plies.

- 5 13. A composite sole in blank of vulcanizable elements adapted to be trimmed to a template, comprising a thin, fabric-backed tread ply and a top cover ply having an exposed surface adapted to unite with a shoe
10 bottom, said tread and top ply united to form a flat marginal excess; a resilient pad comprising a rubberized textile breaker marginally short of the edge of the said flat marginal excess and tapering centrally in
15 thickness therefrom, said breaker completely enveloped by said tread and top plies.

14. A composite sole in blank, comprising a vulcanizable rubber tread and top cover ply marginally unified to form a flat perim-
20 etral trim excess; a resilient breaker ele-
ment of vulcanizable rubberized textile fabric enveloped by said tread and top plies and ta-
pering from edges short of the said flat mar-
ginal portions toward the central area of said
25 breaker; said sole having edge portions sub-
stantially thinner than its central area.

In testimony whereof I affix my signature.
NORMAN WALLACE.
